UNITED STATES PATENT OFFICE.

SYLVESTER V. LOSEY, OF DETROIT, MICHIGAN.

PROCESS AND APPARATUS FOR RECHARGING MAGNETS.

Application filed May 24, 1926. Serial No. 111,449.

My invention relates to improvements in a process and apparatus for recharging magnets especially those magnets that form part of magnetos, and it consists in the steps hereinafter disclosed and in the apparatus for carrying out the same.

An object of my invention is to provide a process of recharging weak magnets of magnetos such as that used in the Ford automobile without the necessity of removing the magnets or coils.

A further object of my invention is to provide a process for recharging magnets of magnetos of the type while the parts are in their normal position by the use of alternating current which during the charging process may demagnetize the magnets thereby permitting them to drop any magnetizable particles which may have caused a short-circuit, and of subsequently recharging the magnets to their full capacity.

A further object is to provide a recharging process which when the connections have been made may be carried out almost instantaneously and at a minimum cost of electrical energy.

A further object is to provide a novel form of apparatus for making the connections by means of which the process may be carried out and for testing the apparatus after the operation has been completed.

Other objects and advantages will appear in the following specification, and the novel features of the invention will be particularly pointed out in the appended claims.

My invention is illustrated in the accompanying drawings, forming part of this application, in which

Figure 1 is a plan view of a portion of the apparatus,

Figure 2 is a sectional view on the line 2-2 of Figure 1, and

Figure 3 is a diagrammatical view showing the circuit connections.

In carrying out my invention I provide a casing 1 which may be made of wood, hard rubber, or other suitable material. Disposed in the top of the casing is a volt-meter 2 of the alternating current type such as is used in connection with the testing of the magnetos of Ford automobiles. This voltmeter is connected to the socket member 3 of the plug, as shown in Figure 1.

A second plug member 4 is carried by the top of the casing. One terminal of this plug member is connected through a resistance

5 with a spring clip 6, the other terminal being connected through a resistance 7 with a spring clip 8. The male member 9 of the plug has one terminal 10 connected with a spring clip 11, the other terminal 12 being connected to a conducting bar or rod 13 carried by an insulating handle 14.

From the foregoing description of the various parts of the device, the operation thereof may be readily understood. Let us assume that the generating circuit of a Ford automobile has deteriorated through the losing of a charge by the magnets of the magneto and further that some magnetizable conducting particles are being held by the magnets and thus dissipating the charge. In Figure 3 I have shown diagrammatically the arrangement of the magnets M as they occur in the Ford magneto. The coils C are shown disposed in their relation with the magnets.

In using the apparatus, the plug member 9 is first connected to the plug member 4. The spring clips 6 and 8 are connected to the conductors 15 and 16 which lead from the line wires 17 and 18 respectively. The voltage used is preferably 220 volts although it may be more for season explained later. The resistances 5 and 7 are used to prevent excessive flow of current. The clip 11 is fastened to one end of the coil as at 19. This may be at a terminal on the dash. As long as the conductor 13 is not grounded, no current will flow, but on touching the end of the conductor 13 to ground, such as to the radiator, fender, or other portion of the automobile, alternating current will flow through the coils C. Now I have found that in practice all that is necessary is to make quick taps or contacts of the end of the conductor 13 in order to recharge the magnets to their full capacity.

Apparently if such contact is made when the wave of the current is such as to demagnetize the magnets, this will occur, and any magnetizable material which is being held by the magnets will be loosened and will fall away from the magnets and the coils. A subsequent short contact or tap will recharge the magnets completely. It is, of course, possible that the second contact will catch the same part of the alternating current wave that the first one did, but a few taps is generally sufficient to recharge the magnets since in a few trials I have found that the magnets will be charged to their full capacity.

In order to test whether the charging operation has been successful, it is only necessary to withdraw the plug member 9 and insert it in the plug member 3. Now by grounding the end of the conductor 13 the volt-meter should register a full voltage for a Ford magneto, thus indicating that the magnets have been restored to their full strength.

10 It is entirely possible to recharge the magnets to a workable strength at a lower voltage than 220, but I prefer 220 as stated since this has proved to be in practice the most satisfactory voltage.

15 It will be understood, of course, that the short contact or tap may not permit such current to flow as might be permitted by a longer contact, but I have found that even where there is a longer contact so that the 20 magnets are being charged and discharged rapidly by the alternating current the effect is substantially the same as of the momentary contact. Since the momentary contact closure of the circuit works as well as a prolonged closure, I find that the work of 25 charging the magnets may be done in a very short time. In some instances, prolonged closure of the circuit may be injurious to the coils where a momentary connection is not 30 injurious. Thus in many cases a magneto may be almost instantly rejuvenated by a few taps of the conducting member 13 on a grounded portion of the automobile. During 35 this time the magnets may be de-energized to drop any magnetizable particles that may cause a short-circuit and may be re-energized to their full capacity so that all that is necessary is to start the engine by the cranking of the magneto either by hand or 40 by a starter as the case may be. The apparatus for accomplishing the recharging is light in weight and may be easily carried by hand to the place where the recharging is to be done.

45 I am aware that direct currents have been used in the coils of magnetos of the Ford type for re-magnetizing the magnets but such a process would not fulfill the purposes of my invention since where direct current 50 is used it is customary to determine the polarity of the magnets so that the passage of the current will tend to increase the magnetism. By the use of the alternating cur-

rent the magnetism is decreased, thus permitting the magnets to discharge any magnetizable material which may have adhered to them and then to recharge the magnets. This of course is not done where a direct current is used in the coils.

55 In addition to the advantages above enumerated there is another advantage which is very important. One or more of the field coils of the magneto may be short-circuited through the lodgment of a particle of conducting material. This is more liable to occur at or near the wires which connect the adjacent coils or it may be an imbedded substance which is thrown in by force.

60 Now when the terminal 13 is grounded, it sends a current through this shorted part, 70 burning out the material which has caused the short-circuit and thus eliminating the short-circuit and restoring the circuit to normal through the coils.

65 Another feature to which I desire to call 75 attention is the fact that if in assembling charged magnets of a magneto of the Ford type one should inadvertently place north poles where south poles should be he need not disassemble the parts, but he can proceed to finish the device and the polarity of the magnets can be reversed by the process set forth above. Furthermore, this can be 80 done almost instantly.

I claim:

85 1. In a process of recharging magnets of 90 magnetos of the Ford type, the herein described steps which consist in passing through the field coil circuit an impulse from an alternating current to de-energize the magnets, and subsequently passing an impulse from the same alternating current to energize the magnets.

95 2. In a process of recharging magnets of 100 magnetos of the Ford type, the herein described steps which consist in passing through the field coil circuit which has become grounded an alternating current of a voltage considerably higher than that given out by the magneto, whereby the grounding connection is burned out, and in subsequently passing an impulse from the same alternating current through the coils to restore the charge of the magnets.

SYLVESTER V. LOSEY.
